UNITED STATES PATENT OFFICE.

JOSEPH RUSSO, OF PASSAIC, NEW JERSEY.

ANTITHIEF MILK-BOTTLE HOLDER.

Application filed November 25, 1922. Serial No. 603,157.

To all whom it may concern:

Be it known that I, JOSEPH RUSSO, a citizen of the United States, residing at Passaic, in the county of Passaic and State of New Jersey, have invented certain new and useful Improvements in Antithief Milk-Bottle Holders, of which the following is a specification.

This invention relates to an anti-thief milk bottle holder which may be mounted on the door of a house or apartment to receive the full milk bottle and lock the same so as to prevent it being stolen.

The invention has for an object the provision of a novel type of milk bottle holder which receives and locks the full milk bottle without requiring any special manipulation by the milkman, a further object relating to the provision of a device for holding a number of bottles.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view showing my improved milk bottle holder in position on the door of a house.

Fig. 2 is a longitudinal vertical sectional view thereof, this view being taken on the line 2—2 of Fig. 3.

Fig. 3 is a transverse vertical sectional view thereof, this view being taken in general on the line 3—3 of Fig. 2.

Fig. 4 is a horizontal sectional view taken on the line 4—4 of Fig. 2.

Fig. 5 is a similar view to Fig. 2, but showing the parts in a different position.

Referring now to the drawings the reference numeral 10 indicates a rectangular box having one face in the form of a plate 10' adapted to be fixed on the door such as 11, of a house or of any dwelling, the fastening means being accessible only from the inside of the dwelling.

Fixed to the inner side of the opposite wall of the box 10 is a plate 12 on which is slidably mounted a bolt 13 having mounted thereon and spaced longitudinally thereof a pair of short, vertically arranged, semicylindrical jaw members 14 which co-operate with like member 15 fixed to the plate 12 in engaging the neck of the bottle to support

the latter in the holder. These jaws 14 and 15 may have outwardly flared lower ends 14' and 15'. The bolt 13 is formed with a rod-like extension 16 around which is coiled an expansion spring 17 which urges the jaw 14 toward the jaw 15. This spring bears at one end against an eye 18 fixed to the plate 12 and through which the element 16 passes freely, this eye forming one of the guide supports for the bolt, the other support being in the form of a pin 19 fixed to plate 12 and projecting into a longitudinal slot 20 in the bolt. The bolt 13 has a semi-circular notch 22 in the lower edge thereof adapted to be engaged by the bit of a key 70 which may be inserted in a key-hole 23 in the face of the box 10. A small cover plate 24 is placed over the bolt, being secured to the plate 12 and serving to limit the inward movement of the key and prevent transverse 75 displacement of the bolt.

The bottom of the box 10 is formed with openings of the proper size and shape to receive the milk bottles B, which apertures are surrounded by an inwardly flaring up-standing flange 28 against which the shoulder formed at the junction of the neck and body of the bottles rest when the bottles are inserted upwardly to place.

The jaws 14 are formed on their upper 85 edges with notches 32 in which engage the tips or projections 33 on the lower ends of flat springs 34 depending from the top of the box.

In the use of this modified form of 90 the device the bottles are inserted in place by being pushed upwardly through the openings in the bottom of the box 10, the upper end of each bottle engaging and pushing aside the jaw 14 on the bolt 13, 95 the jaw snapping into place under the thickened lip b at the top of the bottle and in conjunction with the jaw 15 holding the bottle in place; the tips 33 of the springs 34 engaging under the lips b, 100 at the mouths of the bottles. When the bottles are to be removed the bolt 13' is retracted, freeing the jaws from the bottle necks. The bottles however, remain supported by the springs 34 (which are of sufficient stiffness for this purpose) and are then pulled downwardly by hand to release them. These springs 34 also serve to hold the first bottle in place when the bolt 13' is pushed back as the second bottle is inserted. 110

It will be understood of course that the device might be constructed to hold a larger number of bottles.

As indicated in Fig. 5 the notch 22^a which is engaged by the key-bit K is arranged so that the key-bit, when turned to retract the bolt, acts to hold the bolt retracted, a pin 36 limiting the turning movement of the said bit.

10 A pair of spring clips 30 may be mounted on one end of the box to hold the empty bottle to be taken by the milkman.

Having thus described my invention what I claim as new and desire to protect by Letters Patent of the United States is as follows:

1. A device of the class described comprising a box having an opening therein, a pair of co-operating bottle gripping jaws in registry with said opening, a spring-pressed bolt on which one of said jaws is mounted,

said bolt being adapted for retraction by a key, the said jaws being formed to loosely encircle the neck of the bottle when in operative position, and comprising short semi-cylindrical members having outwardly flared entrance ends and means adapted to yieldingly support the bottle when the bolt is retracted.

2. In a device of the class described, a key-operable bolt, a pair of bottle gripping jaw elements spaced therealong, a pair of fixed bottle gripping jaw elements adapted to co-operate with the first named elements, and springs arranged adjacent the first named jaw elements adapted to yieldingly engage under the lip of the bottle to yieldingly support the latter when the said bolt is retracted.

In testimony whereof I have affixed my signature.

JOSEPH RUSSO. [L. s.]
